UNITED STATES PATENT OFFICE.

JOHAN EMIL ERIKSEN, OF OSLO, NORWAY.

APPARATUS FOR REGULATING SPEED VARIATIONS IN POWER ENGINES EXPOSED TO VARYING LOAD.

Application filed October 29, 1926. Serial No. 145,081.

- The present invention relates to the regulation of the speed of power engines exposed to varying load, as an example, in the case of marine-engines when the propeller is lifted from the water. In this event the admission of steam to the engine should be arrested momentarily in a positive manner if the usual manipulation by means of the throttle valve is to be omitted.
- 10 The present regulating device is adapted to act momentarily and positively whether the variations of speed of the power engine are rapid or slow, and the effect is obtained by using centrifugal bodies in combination 15 with a fly-wheel, the action caused by the relative variations of speed between the swinging-motion of the centrifugal bodies and the inertia of the flywheel being used to control the admission of pressure fluid to a 20 piston which in turn controls the admission of pressure fluid to the power engine.
- The invention is illustrated as an example in the accompanying drawings.
- Figure 1 is a vertical axial sectional view 25 of the improved regulating device.
- Figure 2 is a detail transverse sectional view on the plane disclosing the fly wheel and the governor weights.
- Figure 3 is a detail plan showing a portion 30 of the sleeve and also showing the yoke, the coupling member and one of the segments which coacts with the sleeve to operate the coupling member.
- The apparatus shown comprises a shaft 1 carried in a bearing 2. On said shaft is rotatably mounted a sleeve 3 upon which a belt-pulley 4 is fastened by a key and on which the flywheel 5 is loosely mounted. In the hub 35 of the belt-pulley are disposed two pins 6 diametrically of each other. These pins project parallel to the shaft into a recess in the flywheel 5 and support two centrifugal bodies 7 which at their free ends are connected to springs 7^a forcing them inwards against the 40 action of centrifugal force. The springs are connected at their opposite ends to pins projecting from the pulley 4. The centrifugal bodies 7 are formed as double levers the parts 9 projecting inwardly and engaging notches 8 in the hub 10 of the flywheel 5. The said hub 45 is provided with toothed parts 12 meshing with toothed segments 13 which in turn are rotatably supported by pins 14 on a yoke 11 connected to the sleeve 3. The segments 13 50 are provided with lateral arms 13^a which are cams coacting with a coupling member 15 coacting in turn with a slide valve 16 which, after being adjusted will either lead the pressure fluid to a piston 17 or conduct it from same. The piston is normally maintained in 60 its initial position by means of a spring 18. The rod 19 of the piston may be connected in any suitable manner to a throttle-valve or the like.
- The action of the apparatus will be clear 65 from the above description: when the rotary speed of the shaft increases slowly the centrifugal bodies 7 will, owing to increasing centrifugal force be swung outwards and consequently by means of the lever arms 9 and 70 the notches 8 turn the flywheel relatively to the shaft.
- When the speed becomes greater than allowed, the coupling 15 will be moved by the cam arms 13^a and cause the slide valve 16 75 to be adjusted so as to lead pressure fluid behind the piston 17 and force the same with its piston rod 19 to the right for manipulating the throttle valve and simultaneously carry the slide valve back to its initial position. 80
- When the speed is suddenly increased the inertia of the flywheel will prevent its motion and consequently the flywheel will act upon the centrifugal bodies so as to momentarily adjust the slide valve and thereby cause the 85 piston 17 to momentarily arrest the admission of pressure fluid.
- It will be understood that the transfer of angular motion from the belt-pulley or the like and the flywheel as an axial motion to 90 the coupling 15 may be effected by any other means than that described. As an example a screw may be advantageously used instead of the mechanism shown.
- Claims:
1. In an apparatus for regulating the speed in power engines exposed to varying load, a rotatable sleeve, a driving pulley connected to the same, a flywheel mounted loosely on the said sleeve, and having a recess taking up pins for supporting centrifugal bodies, a hub on the flywheel provided with notches coacting with the said centrifugal bodies, and means for transferring the relative adjustment of the said parts to a device controlling the admission of pressure fluid to the power engine.
  2. In an apparatus for regulating the speed in power engines exposed to varying load, a rotatable sleeve, a driving pulley

connected to the same, a flywheel mounted loosely on the said sleeve, centrifugal bodies mounted on the pulley, a hub on the fly wheel provided with notches coacting with the said 5 centrifugal bodies, means for transferring the angular adjustment of the said parts to an axial motion, an auxiliary cylinder, a piston therein, engine throttle valve controlling means connected to and operated by said piston, a slide valve controlling the admission of pressure fluid to and the outlet of pressure fluid from said auxiliary cylinder to actuate said piston and hence also said engine throttle valve controlling means.

15 3. In apparatus for regulating the speed of power engines exposed to varying load, a sleeve mounted for rotation, a driving pulley fast to the sleeve, centrifugally acting bodies mounted on the said pulley, a fly wheel 20 mounted loosely on the sleeve and provided with notches coacting with the centrifugal bodies and also provided with gear teeth, turnable tooth segments coacting with said gear teeth of the fly wheel, a yoke fast to the 25 sleeve and on which said segments are mount-

ed, member movable by said segments, a cylinder, a piston therein, a valve to control admission of steam to the cylinder for action on said piston, said valve being opposed to the piston and being connected to said member which is movable by said segments and an engine throttle valve controlling member connected to said piston for operation thereby.

4. In apparatus as claimed in claim 3, in 35 which the piston is moved by steam in one direction and a spring is employed to move the piston in the reverse direction.

5. In a power engine, a flywheel, a piston, a centrifugally actuated device coacting with 40 said flywheel, a valve device, means for transferring the adjusting motion of the flywheel to said valve device for controlling the admission of pressure fluid to said piston, and means 45 acted upon by the said piston for adjustment of the supply of pressure fluid to the power engine.

In testimony whereof I affix my signature

JOHAN EMIL ERIKSEN.
